UNITED STATES PATENT OFFICE.

HENRY SPENCER BLACKMORE, OF MOUNT VERNON, NEW YORK, ASSIGNOR,
BY DIRECT AND MESNE ASSIGNMENTS, TO BLACK-FORD UTILITY OIL
COMPANY, A CORPORATION OF THE DISTRICT OF COLUMBIA.

PROCESS OF SEPARATING SULFUR FROM THE SULFUR-CONTAINING CONSTITUENTS OF PETROLEUM AND
MAKING HYDROGEN CARBID.

SPECIFICATION forming part of Letters Patent No. 793,026, dated June 20, 1905.

Original application filed September 7, 1904, Serial No. 223,625. Divided and this application filed October 29, 1904. Serial No. 230,550.

To all whom it may concern:

Be it known that I, HENRY SPENCER BLACKMORE, a citizen of the United States, residing at Mount Vernon, in the county of Westchester and State of New York, have invented certain new and useful Improvements in Processes of Separating Sulfur from the Sulfur-Containing Constituents of Petroleum and Making Hydrogen Carbid, of which the following is a specification, being a division from my application, Serial No. 223,625, filed in the United States Patent Office September 7, 1904.

The object of my invention is to separate sulfur from sulfur-containing petroleum and similar compounds and produce hydrogen carbids in such a manner as to facilitate purification, effect a saving in time and labor, thereby economizing the cost; and it consists in exposing the sulfur-containing petroleum to the action of an alkali-earth-metal carbid, such as calcium carbid, at a reacting temperature.

In carrying out my invention on a practical basis I proceed as follows, reference being had to the accompanying drawings, in which—

Figure 1 is a vertical transverse section through the line *xx* of Fig. 2, showing retorts partially filled with metal carbid. Fig. 2 is a vertical longitudinal section through the line *yy* of Fig. 1; and Fig. 3 is a front view of the purifying apparatus, showing outlet-pipes.

Similar letters of reference indicate like parts in the various views.

A designates a retort made of any suitable material and provided with the heads *B* and *B'*, the said heads being held against the flange of the retort *A* by means of the screw-clamp *C*. Through the heads *B* pass the inlet-pipe *D*, provided at the inner end with a deflector or spreader *e*. The retort *A* is provided at or near the end closed by the head *B'* with a suitable outlet-pipe *h*, controlled by valves *I*, said pipes communicating with a common outlet *K*. Retorts *A* are preferably heated by means of gas-burners *L*, which are so arranged as to throw the flame directly under the re-

torts, whereby the temperature may be regulated and maintained uniformly.

In employing the apparatus, as described, in the separation of sulfur from sulfur-containing petroleums I fill the retorts *A* with granulated calcium carbid about two inches deep over the entire bottom. I then close the retort or receptacle and introduce into and pass through the retort *A* a current of vaporized sulfur-containing petroleum from the inlet-pipe *D*, which is thrown upon the surface of the carbid by the extended depending spreader or deflector *e*. As the sulfur-containing petroleum passes over the calcium carbid the calcium absorbs the sulfur therefrom, producing a substance which is practically free from sulfur. The reaction which takes place may be illustrated by the following chemical formula or equation, which illustrates the action of calcium carbid on methyl sulfid, a hydrocarbon compound containing sulfur, analogous in action to sulfur-containing petroleum:

or

70

75

It will be noted in the foregoing equations that the sulfur is removed from the hydrocarbon, forming calcium sulfid, while the carbon of the calcium carbid unites with a portion of the freed hydrocarbon, producing two molecules of hydrocarbon of less density than the one molecule of sulfur-containing hydrocarbon acted upon. It is found in the sulfur-containing petroleums that the heavier products predominate over the lighter, the reason for which appears to be that the lighter hydrocarbons are condensed by the coupling or joining action of the sulfur combined there-

80

85

90

with, upon removal of which by the action of a carbid, such as calcium carbid, the heavier product is transformed into hydrocarbons of lighter or less dense character. This does not 5 appear to be the case where the sulfur is removed by such agents as copper oxid or other simple sulfur-extracting or absorbing agents in which the hydrocarbon from which the sulfur is abstracted condenses upon itself, producing products of the heavier hydrocarbon 10 type.

The advantage attained by the employment of a carbid, such as calcium carbid, will be seen when it is understood that the heavier 15 sulfur-containing hydrocarbon products are transformed by the action of carbids, such as calcium carbid, into lighter hydrocarbons, such as kerosenes or illuminating-oils, from the otherwise more dense paraffin products.

20 After the sulfur has been abstracted from the sulfur-containing oils or petroleum products the purified vapor passes out of the retort or receptacle through the pipes *h* and the conduit *K* to a suitable reservoir. (Not shown.)

25 In starting the reaction it is sometimes advisable to heat the retort or receptacle by means of the burners *L* to about 360° Fahrenheit, the draft being controlled by the dampers *zz*. It is found, however, that during the reaction 30 between the sulfur of the sulfur-containing hydrocarbon and the carbid considerable heat is liberated internally, whereupon after inducing the reaction by means of the initial heating the burners *L* may be shut off and 35 the reaction continued by the heat liberated during the transformation or purification.

I can use or employ any available sulfur-containing hydrocarbon or sulfurous petroleum, either in a gaseous or vaporized condition or in a pure fluid condition, and I can employ any other alkali-earth-metal carbid in place of calcium carbid aforesaid, so long as the sulfur of the sulfur-containing hydrocarbon or sulfurous petroleum has such an affinity 45 for the base of the carbid that it is withdrawn or separated therefrom when brought in contact therewith.

The term "alkali-earth-metal carbid," as employed in this specification and claims, relates 50 to a compound or union of carbon with an alkali-earth metal, be it a normal carbid, acetylid, or other union of carbon with the metal or metals aforesaid.

The processes devised in the prior art for 55 the purification from or the removal of sulfur from sulfurous petroleum or its products have for their object the abstraction of the sulfur content with the destruction of the hydrocarbon to which the sulfur is joined without supplying any available ingredient in lieu of the sulfur abstracted, while in my process the hydrocarbons left after the abstraction of the sulfur content of the sulfurous petroleum are augmented or increased in value to the 60 extent of the substitution of the carbon for

the sulfur content removed, thereby not only removing the sulfur with the purification of the petroleum, but simultaneously producing an equivalent of hydrocarbon as a substitute for the sulfur eliminated, which hydrocarbon 70 exists in a lighter form and is more available for illuminating purposes.

When the process is employed for the removal of sulfur from sulfurous petroleum, such as Lima oil, I prefer to first vaporize 75 the oil by the action of heat and convey this vaporized mixture of hydrocarbon and sulfo-hydrocarbon in contact with the alkali-earth-metal carbid, as aforesaid; but I do not confine myself to this particular method of 80 procedure, as the carbid may be introduced in the liquid of liquefied sulfur-containing hydrocarbon or petroleum, or brought in contact therewith, or exposed to the action thereof, in any convenient manner. 85

The term "gaseous," as employed herein, is intended to include substances of vaporous nature or those which may be vaporized by the action of heat.

90 My process is not only available for the purification of gaseous, vaporous, or vaporized hydrocarbons or sulfo-hydrocarbons, (sulfurous petroleums,) but is applicable to the purification of the more solid constituents of the petroleums—such as paraffin, petrolatum, &c.— 95 and I do not desire to confine myself to the purification of petroleum as a composite composition, but reserve the right to purify any individual product of the sulfur-containing 100 petroleums which may be or may have been separated into its individual products by fractional distillation or otherwise prior to separating the sulfur therefrom, whereby the individual ingredients of the petroleum may be purified separately instead of collectively, as 105 is the case where the petroleum is vaporized as a whole direct and purified by the abstraction of the sulfur before separation of the individual ingredients.

Having now described my invention, what 110 I claim as new, and desire to secure by Letters Patent, is—

1. The process of removing sulfur from petroleum containing the same, which consists in exposing sulfur-containing petroleum to 115 the action of an alkali-earth-metal carbid.

2. The process of removing sulfur from petroleum containing the same, which consists in exposing sulfur-containing petroleum to the action of calcium carbid. 120

3. The process of removing sulfur from the constituents of petroleum, which consists in exposing the sulfur-containing constituent to the action of an alkali-earth-metal carbid.

4. The process of removing sulfur from the constituents of petroleum, which consists in exposing the sulfur-containing constituent to the action of calcium carbid. 125

5. The process of removing sulfur from oil containing the same, which consists in expos- 130

ing the sulfur-containing oil to the action of an alkali-earth-metal carbid.

6. The process of removing sulfur from oil containing the same, which consists in exposing the sulfur-containing oil to the action of calcium carbid.

7. The process of producing hydrogen carbid, which consists in exposing an alkali-earth-metal carbid to the action of sulfurous petroleum at a reacting temperature.

8. The process of producing hydrogen carbid which consists in exposing calcium carbid to the action of sulfurous petroleum at a reacting temperature.

15 9. The process of producing hydrogen carbid which consists in vaporizing sulfurous petroleum and exposing the same to the action of an alkali-earth-metal carbid.

10. The process of removing sulfur from sulfurous petroleum, which consists in exposing it to the action of an alkali-earth-metal carbid at a reacting temperature. 20

11. The process of purifying petroleum which consists in exposing the petroleum to the action of an alkali-earth-metal carbid. 25

12. The process of purifying petroleum which consists in exposing vaporized petroleum to the action of an alkali-earth-metal carbid.

In testimony whereof I affix my signature in 30 presence of two witnesses.

HENRY SPENCER BLACKMORE.
